[57] **CLAIM**

The ornamental design for a sink, as shown and described.

DESCRIPTION

FIG. 1 is a perspective view taken from the top, front and right side of a sink showing my new design; FIG. 2 is a top plan view thereof; FIG. 3 is a cross-sectional view taken on line 3—3 of FIG. 2; FIG. 4 is a cross-sectional view taken on line 4—4 of FIG. 2; FIG. 5 is a cross-sectional view taken on line 5—5 of FIG. 2; FIG. 6 is a cross-sectional view taken on line 6—6 of FIG. 2; and, FIG. 7 is a perspective view taken from the top, front and right side of a second embodiment thereof. The broken line representation of holes in FIGS. 1 and 7 are for purposes of illustration only and form no part of the claimed design.
